UNITED STATES PATENT OFFICE.

ABEL MAGUI, OF NEW YORK, N. Y.

DESIGN FOR A LIGHTING-FIXTURE.

44,482.

Specification for Design.

Patented Aug. 12, 1913.

Application filed May 14, 1913. Serial No. 767,712. Term of patent 7 years.

To all whom it may concern:

Be it known that I, ABEL MAGUI, a citizen of the United States, and a resident of the city of New York, county of New York, State of New York, and whose post-office address is 809-811 Freeman street, in said city, have invented a new, original, and ornamental Design for a Lighting-Fixture, of which the following is a specification, reference being had to the accompanying drawing, forming part thereof.

Figure 1 is a plan view of the lighting fix-

ture showing my new design. Fig. 2, is a side elevation of the same.

I claim:

The ornamental design for a lighting fixture, as shown.

Signed at the city, county and State of New York, this 12 day of May, 1913.

ABEL MAGUI.
